HOIST.

1,177,265.

Specification of Letters Patent. Patented Mar. 28, 1916.

Application filed July 28, 1915. Serial No. 42,252.

To all whom it may concern:

Be it known that we, WILLIAM B. PAVEY and GEORGE M. FRENCH, citizens of the United States, residing at Chicago, in the county of Cook and State of Illinois, have invented certain new and useful Improvements in Hoists, of which the following is a specification.

Our invention relates to improvements in hoists particularly for use in connection for elevators and the like such as may be driven by hand or other power.

One object of our invention is to provide a hoist which will at all times be positively held against return or fall against the will of the operator by means of a ratchet or other such rigid non-return mechanism.

Another object of our invention is to provide means which will insure the release of the load without danger to the operator and without possibility of getting out of control of the operator.

Another object is to provide a hoist which may be lowered as rapidly as need be without getting out of control of the operator and without being limited to the speed at which the operator can turn the crank.

Other objects of our invention will appear in the specification.

The invention itself is illustrated more or less diagrammatically in the accompanying drawings, wherein—

Figure 1 is a side view part in section and part in elevation with parts broken away;

Fig. 2 is a detail side elevation in part section showing the brake; Fig. 3 is a detail side elevation in part section showing the ratchet.

Like parts are indicated by like letters throughout the several figures.

A, A is a frame work of the usual type. Mounted for rotation within it is the hoist drum A¹ about which is wound the hoist cable A².

A³ is a gear mounted for rotation with the drum. In mesh with it is an idler pinion A⁴ which in turn is mounted for rotation on the shaft A⁶.

A⁵ is an idler gear mounted for rotation on the shaft A⁶ with the pinion A⁴.

B is the hoisting or crank shaft rotatably mounted at one end in a bearing B¹ adjacent which bearing is a thrust collar B² rigidly attached to the shaft B.

B³ is a thrust washer of fiber or yielding material rotatably mounted on the shaft B and adapted to engage at one side the thrust collar B², and at the other side the steel or metal washer B⁴.

B⁵ is a drive sleeve rotatably mounted on the shaft B and carrying the pinion B⁶ in mesh with the gear A⁵. At the other end of the drive sleeve B⁵ is a brake pulley B⁸.

B¹⁰ is a brake band surrounding the brake pulley B⁸ and adapted to be tightened on the pulley by the operator by means of the screw B¹¹. It is held against rotation by the shaft A⁶ upon which a portion of the band is pivotally mounted.

C is a combined sleeve and nut screw-threaded on the end of the shaft B having rigidly mounted thereon the hand crank C¹. This sleeve passes through the bearing C² on one of the frames A and is free to rotate on and slide along the shaft. At its inner end it is thrust against the ratchet wheel C³ which is provided with ratchet teeth C⁴ in opposition to a dog C⁵ on the shaft A⁶. Between this wheel and the brake pulley B⁸ is interposed a thrust washer of fiber or other suitable material C⁶.

C⁹ is a nut on the inner end of the sleeve C for the purpose of limiting its longitudinal movement within its bearing. It will be noted that the crank is socketed and engages the polygonal end of the sleeve or nut and may be removed therefrom. It is perfectly obvious that other driving means might be used.

In order to insure that the quill or sleeve B⁵ will not float, and to insure that when it turns it will turn the shaft unless the shaft is locked, we provide the spring D contained within the quill pressing at one end on a shoulder D¹, the other end on a washer D², which washer rides against the ratchet wheel C³.

When the crank is turned the nut screws up on the shaft with the shaft at rest until the nut, the ratchet wheel, the driving sleeve and the intermittent friction disks or plates are all clamped rigidly together against the thrust collar. When this takes place a further rotation of the crank will cause the shaft and the driving sleeve to rotate thus operating through a chain of gears to rotate the drum. The ratchet wheel meanwhile rotates with the rest. This continues as

long as rotation of the crank or rotation of the nut in response to the crank, or other driving means continues. When rotation of the crank stops everything else stops. If 5 the operator lets go of the crank the tendency will be first with the weight on the cable to rotate all the parts back until the ratchet wheel is held by the ratchet, then the weight tending to rotate the drum will 10 tend to rotate the driving sleeve. This will make the shaft rotate and the shaft will now rotate into the nut and tend to tighten it against the inertia of the nut and crank. This will clamp the parts against the ratchet 15 wheel so that as experience shows the ratchet even though only frictionally attached to the load is quite sufficient to hold the load at any place where it is left. If now the operator rotates the crank in the opposite 20 direction the load will follow the crank just fast enough to keep the parts together. This also experience shows to be the case, but by this method the load will be lowered only as fast as the operator can turn the crank. 25 When it is desired to lower the load at a more rapid rate the brake is locked on the brake wheel so as to hold that wheel and the shaft rigidly against rotation. The operator then rotates the crank enough to 30 release the pressure tending to press the parts along the shaft. If the brake were not free the shaft would be rotated by the load and catch up with the crank, but since the brake holds it the shaft can not rotate 35 and so the crank may be rotated on the shaft until the end of the sleeve presses against the inner end of the housing. The result of this will be to compress the sleeve on the opposed end of the shaft against the inner 40 end of the bearing at the opposed end. This will hold the shaft frictionally against rotation. The operator then releases the crank leaving it on that position and manipulates the brake on the brake pulley. 45 When he releases this brake the load tends to unwind the drum and rotate the driving sleeve. Since the shaft can not turn, being held frictionally against turning, there is no tendency for it to screw into the sleeve and 50 tighten up the parts against the ratchet and the operator is free to manipulate the load by means of the brake and brake band alone.

We claim:

1. A hand hoist comprising a rotatable 55 shaft, a driving member therefor, a power transmission member rotatably mounted on and in frictional engagement with the shaft, a ratchet wheel rotatably mounted on the shaft in frictional engagement with the 60 transmission member, means responsive to relative rotation of the shaft and driving member for holding the transmission member and shaft against relative rotation, means independent of the shaft for holding 65 the transmission member against rotation

and means responsive to relative rotation of the shaft and driving member for holding the shaft against rotation.

2. A hand hoist comprising a rotatable shaft, a driving member therefor, a power 70 transmission member rotatably mounted on and in frictional engagement with the shaft, a ratchet wheel rotatably mounted on the shaft in frictional engagement with the transmission member, means responsive to 75 relative rotation of the shaft and driving member for frictionally holding the transmission member and shaft against relative rotation, means independent of the shaft for frictionally holding the transmission member 80 against rotation and means responsive to relative rotation of the shaft and driving member for frictionally holding the shaft against rotation.

3. A hand hoist comprising a rotatable 85 shaft, a driving member therefor, a power transmission member rotatably mounted on and in frictional engagement with the shaft, a ratchet wheel rotatably mounted on the shaft in frictional engagement with the 90 transmission member, a locking pawl in engagement with the ratchet wheel, means responsive to relative rotation of the shaft and driving member for locking the transmission member, the shaft and the ratchet 95 wheel together, independent means for holding the transmission member against rotation and means responsive to relative rotation of the shaft and driving member for holding the shaft against rotation. 100

4. A hand hoist comprising a rotatable shaft, a driving member therefor, a power transmission member rotatably mounted on and in frictional engagement with the shaft, a ratchet wheel rotatably mounted on the 105 shaft in frictional engagement with the transmission member, a locking pawl in engagement with the ratchet wheel, means responsive to relative rotation of the shaft and driving member for frictionally locking 110 the transmission member, the shaft and the ratchet wheel together, independent means for frictionally holding the transmission member against rotation and means responsive to relative rotation of the shaft and 115 driving member for frictionally holding the shaft against rotation.

5. A hand hoist comprising a rotatably mounted shaft, bearings therefor, a shoulder on one end thereof, a transmission sleeve 120 rotatably mounted upon the shaft in frictional engagement with said shoulder, a pinion and a brake drum both carried by the sleeve, a brake adapted to engage the drum, a ratchet wheel rotatably mounted on 125 the shaft and in frictional engagement with the end of the sleeve, a combined sleeve and nut screw-threaded and slidably mounted on the end of the shaft opposed to the shoulder and means for rotating said nut on said 130

shaft to move it longitudinally toward said shoulder to clamp the sleeve and ratchet wheel between it and the shoulder frictionally to prevent relative movement and for continuing said rotation of the nut to rotate the shaft and the parts carried thereby to operate the hoist.

6. A hand hoist comprising a rotatably mounted shaft, bearings therefor, a shoulder on one end thereof, a transmission sleeve rotatably mounted upon the shaft in frictional engagement with said shoulder, a pinion and a brake drum both carried by the sleeve, a ratchet wheel rotatably mounted on the shaft and in frictional engagement with the end of the sleeve, a combined sleeve and nut screw-threaded and slidably mounted on the end of the shaft opposed to the shoulder and means for rotating said nut on said shaft to move it longitudinally toward said shoulder to clamp the sleeve and ratchet wheel between it and the shoulder frictionally to prevent relative movement and means for continuing said rotation of the nut to rotate the shaft and the parts carried thereby to operate the hoist, a stop in engagement with said ratchet wheel, and a brake to hold the brake drum against rotation.

7. A hand hoist comprising a rotatably mounted shaft, bearings therefor, a shoulder on one end thereof, a transmission sleeve rotatably mounted upon the shaft in frictional engagement with said shoulder, a pinion and a brake drum both carried by the sleeve, a ratchet wheel rotatably mounted on the shaft and in frictional engagement with the end of the sleeve, a combined sleeve and nut screw-threaded and slidably mounted on the end of the shaft opposed to the shoulder and means for rotating said nut on said shaft to move it longitudinally toward said shoulder to clamp the sleeve and ratchet wheel between it and the shoulder frictionally to prevent relative movement and for continuing said rotation of the nut to rotate the shaft and the parts carried thereby to operate the hoist, a stop in engagement with said ratchet wheel, a brake to hold the brake drum against rotation, a collar carried by

the sleeve, the sleeve rotating means being adapted when moved in the reverse direction to draw said collar against one of the bearings to hold the shaft separately against rotation.

8. A hand hoist comprising a shaft, a support in which it is rotatably mounted, a transmission sleeve rotatably mounted on the shaft, a brake in opposition to said sleeve, a ratchet wheel rotatably mounted on the shaft, a dog in opposition to said wheel, a combined sleeve and nut slidably mounted on and in screw-threaded engagement with the shaft and means for rotating said nut to hold the sleeve and wheel against rotation with respect to the shaft.

9. A hand hoist comprising a shaft, a support in which it is rotatably mounted, a transmission sleeve rotatably mounted on the shaft, a brake in opposition to said sleeve, a ratchet wheel rotatably mounted on the shaft, a dog in opposition to said wheel, a combined sleeve and nut slidably mounted on and in screw-threaded engagement with the shaft and means for rotating said nut to hold the sleeve and wheel against rotation with respect to the shaft and means carried partially by the nut for holding the shaft against rotation.

10. A transmission member comprising a shaft and means for rotating it, a driven member floating upon the shaft, means responsive to the will of the operator for locking such driven member against movement, means responsive to the shaft rotating means for locking the shaft against movement, a ratchet wheel floating on the shaft and in frictional engagement with the driven member and the shaft rotating means, and a dog normally in engagement with the ratchet wheel.

Signed at Chicago, in the county of Cook and State of Illinois, this 23rd day of July, 1915.
